UNITED STATES PATENT OFFICE.

FRED G. VON HOORN, OF TURTLE CREEK, PENNSYLVANIA, ASSIGNOR TO WESTINGHOUSE ELECTRIC & MANUFACTURING COMPANY, A CORPORATION OF PENNSYLVANIA.

TRANSFER SWITCH.

Application filed June 30, 1923. Serial No. 648,706.

To all whom it may concern:

Be it known that I, FRED G. VON HOORN, a citizen of the United States, and a resident of Turtle Creek, in the county of Allegheny and State of Pennsylvania, have invented 5 a new and useful Improvement in Transfer Switches, of which the following is a specification.

My invention relates to switch mechanism 10 and particularly to enclosed switch mechanism for controlling the motors and shutters of moving picture machines.

My improved switch mechanism is particularly adapted for transferring current 15 from the motor operating a moving picture machine to a motor operating another moving picture machine and for controlling the shutter apparatus of the machines, so as to insure proper sequence of operation in transferring the operation from one machine to another.

One object of my invention is to provide a switch mechanism for controlling motors and shutters of moving picture machines 25 wherein a proper sequence of operation of the apparatus controlled by the switch is insured and wherein the switch is automatically returned to a predetermined operating position after each operation.

Another object of my invention is to provide a switch mechanism having the above 30 characteristics, that is simple in operation and inexpensive to manufacture, and which may readily be inspected and repaired.

These and other objects that will be made 35 apparent throughout the further description of my invention are attained by means of the switch mechanism hereinafter described and illustrated in the accompanying drawings wherein—

Figure 1 is a view in vertical section through the housing containing the switch mechanism showing the switch mechanism in front elevation;

Fig. 2 is a view in vertical section through the apparatus taken on the line II—II of Fig. 1 and showing a part of the switch mechanism in side elevation, and

Fig. 3 is a fragmental elevational view of 50 a portion of the switch mechanism taken on the line III—III of Fig. 1.

Referring to the drawings, the apparatus includes a metal housing 4 that may be of any standard construction and which is pro-

vided with a hinged cover 5. The switch 55 mechanism is enclosed within the housing and comprises an insulating base 6 that is secured to the bottom of the housing and which is provided with two pairs of switch contact jaws 7 and 8, and a pair of auxiliary 60 contact terminal members 9 and 11, that are aligned with one of the pairs of contact jaw members 7 and 8, as indicated in Figs. 1 and 2. The switch is of the double-throw, double-pole type and consists of two pairs 65 of blade members 12 and 13, the blade members of each pair being connected by an insulating plate 14 that is secured to the blade members by means of rivets 15. The blade members 12 and 13 are pivoted to hinge jaw 70 members 16 and are permanently held in angular relation as indicated in Fig. 2 by the insulating plate 14. The blades 12 and 13 are of such length that when in the central position indicated in Fig. 2 they conduct- 75 ively engage the contact jaw members 7 and 8.

The switch blade members 12 and 13 are actuated by means of an operating crank rod 17, that is pivoted for rotation in the side 80 walls 18 of the housing 4, the operating rod 17 being disposed within slots 19 in the insulating plates 14. By reason of the lost motion connection between the rod 17 and the slots 19 in the insulating plates 14, it will be 85 seen that the switch blade members 12 and 13 may be rotated even though the axes of the hinge jaws and the operating rod are out of alinement.

A normal operating position of the switch 90 members is indicated at dotted lines A and an extreme operating position of the switch members 12 and 13 is indicated at dotted lines B at which time the switch blade member 13 is in conductive engagement with 95 auxiliary contact member 11. When the switch members 12 and 13 are moved to the extreme lower position, the switch blade member 12 will conductively engage the auxiliary contact member 9.

It will be understood that current to the motor is supplied from a circuit to which hinge jaw members and the contact jaw members are connected and that the motors of two moving picture machines are energized when the switch blade members are in the central position indicated in Fig. 2 in full lines. When the blade member 13 oc-

cupies the position A, the motor connected to the contact jaw member 8 is energized and the motor connected to the contact jaw 7 is disconnected from the circuit. When the 5 switch blade 13 is moved to position B wherein it conductively engages the auxiliary contact terminal 11, it will be understood that a relay controlling the "shutter douser" is momentarily energized and 10 causes the shutter of the machine being put out of service to close.

It is necessary only, to insure proper operation to close the circuit through the 15 switch jaw member 16, switch blade member 13 and auxiliary contact member 11, for the purpose of actuating the relay and after the relay is actuated, it is desirable to automatically interrupt the circuit through the relay. It will be understood that the crank 20 rod 17 is provided with an operating handle 21 that extends exteriorly of the housing and by means of which the switches are actuated. It is desirable, therefore, to automatically move the switch blade member out 25 of engagement with the auxiliary contact member instantly after the contact has been made. The apparatus for accomplishing this will hereinafter be described.

During normal operation of one of the 30 moving picture machines, the switch blade 13 occupies the position A in engagement with the contact member 8. When it is desired to transfer the operation of the moving pictures from the machine in operation to an auxiliary machine, in order to change from one film to another with the least possible interruption, the switch blade members are moved downwardly toward the auxiliary contact member 9. When the 35 switch blade member 12 engages the contact jaw member 7, the motor connected thereto will be energized and operation started before the motor connected to the switch jaw member 8 is deenergized. This operation 40 gives the last starting motor time to pick up and to insure proper operation of the moving picture film before the operation of the other film is discontinued.

Further downward movement of the 50 switch blade members causes the switch blade 13 to be withdrawn from the contact jaw member 8 and switch blade member 12 to be moved into engagement with the auxiliary switch contact member 9. At this instant the blade engages the auxiliary contact 55 9, the "shutter douser" connected to the machine being put out of operation, will be closed, thus interrupting the light of that machine. As soon as the operator has moved 60 the switch to the extreme position, wherein it engages one of the auxiliary contact members, he may release the handle and the apparatus about to be described will return the switch blade member 12 to a position corresponding to the position A with the blade

member in engagement with the switch jaw member 7.

The apparatus for automatically returning the switch blade to the operative position A upon the release of the handle by the 70 operator comprises a metal plate 22 that is attached to the side wall 18 and which is provided with a pair of guide tongues 23 and 24 that are bent outwardly from the plane of the body of the plate 22, as indicated in Fig. 1, to provide stop shoulders 25 and 26, respectively. Crank arms 27 and 28 are pivotally mounted upon the pivot shaft 29 of the crank rod 17, the arm 27 being disposed behind the guide 23 and the crank arm 28 being disposed behind the guide 24 as indicated in Figs. 1 and 3.

The crank arms 27 and 28 are provided with angularly disposed fingers 31 and 32 respectively, that extend across the path of movement of the crank rod 17 and which are adapted to be engaged thereby before the crank arm and switch members are moved to the extreme operative positions B. As indicated in Fig. 3, the crank arm has been moved to the lowermost position and has engaged the finger 32 of the arm 28, thereby moving the arm to its extreme lower position and stretching a helical spring 33 that normally tends to hold the arms 27 and 28 in engagement with the stop shoulders 25 and 26 respectively. It will be apparent that, when the operator releases his grip upon the operating handle 21, the finger 32, which is in engagement with the crank rod 17, will cause the crank rod to be moved to the position corresponding to position A when the spring 33 returns the arm 28 into engagement with the stop shoulder 26.

When the switch blade 13 is moved into contact with the auxiliary contact terminal 11, the crank rod 17 will engage the finger 31 of the arm 27 and stretch the spring 33 which will return the arm 27 to its normal position and move the switch blade member 13 to position A, which is the normal operating position for the motor connected in the circuit containing the switch jaw member 8.

It will be apparent from the foregoing 115 that a simple and inexpensive means is provided for returning the switch blade members to the operating position A after the operator has released his grip upon the operating handle and that the operation is 120 simplified, it being necessary only for the operator to move the operating handle from the position in which he finds it to the extreme opposite position and to release the handle.

While I have illustrated but one embodiment of my invention it will be apparent to those skilled in the art that various changes, modifications, substitutions, additions and omissions may be made in the apparatus il- 130

lustrated without departing from the spirit and scope of my invention, as set forth in the appended claims.

I claim as my invention:

- 5 1. The combination with a double-throw switch having a pivoted blade member, an operating handle therefor and a pair of main contact members adapted to be engaged alternately and simultaneously by
- 10 the switch member, of an auxiliary contact member adapted to be engaged by the switch member while the latter is in engagement with a main contact member and means for automatically moving the switch member
- 15 out of engagement with the auxiliary contact member without disengaging it from the main contact member when the operating handle is released.
- 20 2. The combination with a double-throw switch having a pivoted blade member, an operating handle therefor and a pair of main contact members adapted to be engaged alternately and simultaneously by the switch member, of an auxiliary contact
- 25 member adjacent to each main contact member adapted to be engaged only when the blade member is in contact with the adjacent main contact member, and means for automatically moving the switch member
- 30 out of engagement with the auxiliary contact member without disengaging it from the main contact member when the operating handle is released.
- 35 3. Switch mechanism comprising a pair of main contact members, a pair of auxiliary contact members, a switch member adapted when in middle position to engage both main contact members and when in extreme positions to engage one main contact member and one auxiliary contact member, means for moving the switch member
- 40 to different operative positions and means

for automatically moving the switch member out of engagement with the auxiliary contact member without disengaging it from the main contact member when the first said means is released.

4. Switch mechanism comprising a pair of main contact members, a pair of auxiliary contact members, a switch member adapted when in middle position to engage both main contact members and when in extreme positions to engage one main contact member and one auxiliary contact member, a crank shaft for moving the switch member, a pair of operating arms pivotally mounted upon the crank shaft and adapted to be moved thereby in opposite directions, a stop member for limiting movement of the arms toward one another, a spring yielding holding the arms against the stop and in central position, the said arms having means engaged by the crank arm for moving the crank arm a predetermined distance out of engagement with the auxiliary contact members when the crank shaft is released.

5. Switch mechanism comprising a pair of contact jaw members, a pivot jaw member, a switch member pivoted to the pivot jaw member for simultaneously engaging both jaw members and movable into and out of engagement with the contact jaw members, terminal contact members disposed adjacent to the contact jaw members and adapted to be engaged by the switch member while the switch member is in engagement with an adjacent jaw member, and means for automatically moving the switch member out of contact with the contact

In testimony whereof, I have hereunto subscribed my name this 27th day of June, 1923.

FRED G. VON HOORN.
